VAPOR PRESSURE BOMB

Filed May 2, 1929

UNITED STATES PATENT OFFICE

HARRY LEIGHTON SMITH, OF LONG BEACH, CALIFORNIA, ASSIGNOR TO THE TEXAS COMPANY, OF NEW YORK, N. Y., A CORPORATION OF DELAWARE

VAPOR PRESSURE BOMB

Application filed May 2, 1929. Serial No. 359,783.

This invention relates to an improved apparatus for generating vapor pressure within a closed bomb which will correspond closely to the true vapor pressure of the liquid or mixture thereof to be tested.

The determination of the vapor pressure of pure substances is a comparatively simple problem, but it is essential for accuracy that the two phases, liquid and vapor, be in equilibrium, at the instant the measurement is made. In dealing with pure substance this is not a difficult condition to establish. However, in complex mixtures such as gasoline the components do not vaporize in the same proportions in which they are present in the liquid phase, thus causing a change in the composition of the residual liquid and consequently a change in its vapor pressure or rather what would have been its vapor pressure before the change took place.

Since the surface of contact between the liquid and vapor is the point at which all changes from liquid to gaseous phase or vice versa, take place, it is readily seen that the resulting equilibrium will be governed entirely by the composition and condition of the more or less thin layers of vapor and liquid which are in actual contact. It is possible to produce a uniform composition within each phase by simple agitation but this alone does not ensure that both phases will be of the same composition, and this is largely responsible for unsatisfactory and perhaps inaccurate results obtained with previous methods and apparatus for measuring the vapor pressure of complex mixtures.

It is an object of this invention to provide apparatus for measuring the vapor pressure of a liquid in which error due to lack of equilibrium of the phases is substantially eliminated.

Another object of the invention is to provide apparatus for measuring the vapor pressure of a complex mixture of liquids in which error due to lack of uniformity of composition of the vapor and liquid phases is materially reduced.

A further object thereof is to provide an apparatus with which a close approximation of the true vapor pressure of a liquid or mix-

ture thereof may be produced for the purpose of measuring the same.

A still further object thereof is to provide an apparatus for the generation of a vapor pressure to be measured, in which the vapor space provided is relatively small in order to eliminate non-uniformity of composition of the vapor in said space, and to minimize any change that might take place in the composition of the liquid being tested.

Another object of the invention is to provide a novel apparatus for producing agitation of both the liquid and the vapor to homogenize each phase.

Still another object is to provide means for securing extensive and intimate contact between the material in the two phases, and to agitate the material under test in both phases, the agitation in the vapor phase being by contact between the material of the two phases.

A further object of the invention is to provide a closed vapor generating chamber having means for agitating the contained material, the agitating device being driven preferably by means of an electric motor of induction type having the stator located outside the chamber and the rotor inside the chamber and connected to the agitator to drive the same, thus eliminating a shaft or other driving connection passing through the chamber wall and consequent liability of leakage.

Another object of this invention is to provide apparatus by which the vapor pressure of a liquid or mixture thereof can be measured with speed and accuracy and with little chance of error from leakage.

Other objects and advantages will become apparent in the detailed description of the apparatus embodying the invention which follows.

The drawing is a vertical sectional view of the apparatus for generating the vapor pressure of the liquid to be measured.

The numeral 1 indicates an open vessel suitably supported as indicated at 2 and adapted to contain a temperature controlled fluid such as water for a purpose to presently appear. Secured to the bottom of the ves-

sel 1 and upstanding therefrom within the vessel is a supporting member 3. A cup 4 is formed at the upper portion of this support and is adapted to contain mercury which may be supplied to it from the movable mercury bulb of a conventional mercury manometer in conjunction with which the apparatus herein disclosed is intended to be operated. The purpose of the mercury and a manner of supplying it to cup 4 will be described hereinafter. The bottom of cup 4 may be provided with an extending tubular portion 5 of reduced diameter which passes through an opening in the bottom of vessel 1 and is intended to be connected to the manometer or other pressure measuring device (not shown). Suitable packing 6 may be provided where tube 5 passes through the bottom of vessel 1 to prevent leakage of the water in the vessel through said opening. In the lower portion of cup 4 and upstanding around the junction of tube 5 with the bottom of the cup is an annular flange 7 forming a socket indicated by numeral 8. The interior of the socket may be screw threaded, and an annular shoulder 9 may be formed within the lower portion of the socket for the purpose of supporting a packing washer 10. A pin 11 passes through tube 5 adjacent socket 8 for a purpose to hereinafter appear.

A closed fluid tight chamber 12 adapted to contain the liquid to be tested is formed of an upper tubular portion 13 and a lower portion 14, these being removably joined together in fluid tight engagement by means for pressing annular flanges 15 and 16 together. The lower end of chamber 12 is closed by the central portion of a supporting pedestal 17.

The pedestal 17 is formed with a lower extension 18 of reduced diameter which is externally screw threaded and adapted to be screwed within socket 8 previously described. The center of the pedestal is provided with a bore 19 of stepped diameter, the lower and largest portion of which is internally screw threaded for the reception of an externally threaded hollow plug 20. The lower end of plug 20 is provided with a small aperture 21 and a valve seat 22. The internal diameter of hollow plug 20 is the same as the diameter of the next section of bore 19 and is in alignment therewith. Within this section of the bore and the plug 20 is positioned a valve 23 having a stem 24. The valve is yieldingly pressed into closed position against valve seat 22 by a coil spring 25. The valve is also provided at its lower end with a pin 26 extension of smaller diameter than aperture 21 which extension projects through said aperture and engages with pin 11 to force the valve open against the compression of its spring when the pedestal 17 is screwed into position in socket 8. A number of pas-

sages 27 connect with the upper end of bore 19 and open into the lower part of chamber 12. Hence, when the pedestal 17 is in position in socket 8, communication between chamber 12 and tube 5 is established; but when the pedestal and its supported elements are removed from the socket, valve 23 automatically seats and chamber 12 is closed.

The pedestal 17 is provided with an outwardly extending disc 28 having an annular upstanding flange 29 at its periphery. This flange is internally screw threaded and receives the lower portion of a housing 30 of the stator 31 of the electric motor. The lower edge of the housing is pressed against a packing washer 32 which prevents passage of water into the housing between this edge and the disc 28.

The central portion of the pedestal 18 extends somewhat above the disc portion 28, and around this central portion an annular recess 33 is formed in the upper portion of the disc. The lower end of the lower portion 14 of the chamber 12 is received in this recess, and a packing 34 and packing nut 35 are provided to prevent leakage of the contents of the chamber at this point.

The upper portion of housing 30 is provided with an annular shoulder 36 against which flanges 15 and 16 previously referred to, together with suitable packing 37, and the outer ends of support 38 are clamped by an externally threaded nut 39 which engages a threaded portion of the upper extension 40 of housing 30.

The extreme upper portion of chamber 12 is reduced in diameter and is provided with a transparent tube 41 with graduated scale markings by means of which the volume of the vapor in the chamber may be observed through slot 42 in the wall of the chamber indicated in dotted lines. The inner surface of this reduced portion of chamber 12 adjacent transparent tube 41 is internally screw threaded, and receives a valve assembly indicated generally by numeral 43. The valve assembly may consist of a hollow plug 44 and a valve stem 45 screwed into said plug and the lower end of the stem may be bevelled and form the valve proper. The valve assembly may be screw-threadedly removable from and adjustable within the upper portion of chamber 12 in order to permit replacement and use of various lengths of gage tubes 41. The valve may be provided with a seat at or near the upper end of the gage tube 41. The valve is controlled by manipulation of knurled nut 46 on the upper end of the valve stem. The plug 43 may be provided with a vent tube 47 which opens to atmosphere.

Within chamber 12 there is provided a mechanism for producing the desired agitation of the liquid and vapor contained there-

in. A vertically disposed tube 48, with a small nozzle opening 49 in its upper end and one or more inlet openings 50 in its lower side walls is concentrically supported within 5 chamber 12 by support 38. The tube 48 is so disposed that the outlet opening 49 is adjacent and in axial alignment with the upper reduced portion of chamber 12 and gage tube 41. A vertical shaft 51 extends within 10 tube 48, suitable spacing and guide collars 52 and 53 being provided for holding the shaft in its proper position therein. A number of propeller blades 54 are fixed to shaft 51 at suitable intervals.

15 The rotor 55 of the electric motor previously referred to is positioned within the lower portion of chamber 12 adjacent the stator 31. The shaft 56 of the rotor is rotatably supported at its lower end in ball 20 bearing support 57 in the central portion of pedestal 17.

The shaft 51 is directly secured to and driven by the shaft 56 of the rotor. Thus, when this mechanism is in operation, rotation of rotor 55 and its shaft 56 cause the shaft 51 and propellers 54 to rotate, inducing a circulation of the liquid in chamber 12 upwardly through tube 48, and a fine spray of liquid is projected from nozzle opening 30 49 into the upper and reduced portion of the chamber 12.

The operation of measuring the vapor pressure of a liquid or mixture of liquids with this apparatus is as follows. The vapor pressure bomb, which includes chamber 35 12, stator 31, and pedestal 17, is removed from the water bath by releasing the pedestal from its socket 8. When this is done valve 23 automatically closes. The bomb is then reduced to a low temperature, and may 40 be filled preferably full with a chilled liquid to be tested such as gasoline through valve opening 21. The chilled liquid is forced into the bomb through valve opening 21 from a source, preferably, under a slight 45 pressure. The object of using lowered temperatures is to prevent loss of vapor during the filling operation. The chilling may be expeditiously accomplished by immersing 50 the bomb in the usual ice and salt mixture during the filling operation. During filling of the bomb the valve 45 is opened, thus venting the interior of the bomb through vent pipe 47. Valve 45 is then closed and 55 the bomb is left filled, preferably under a slight pressure.

The movable mercury reservoir of a conventional manometer is then raised until the cup 4 is partially filled with mercury 60 through tube 5. The bomb is then lowered into the water bath (held at the desired temperature by any suitable means) and screwed in place in socket 8. Valve 23, being forced open by pin 11, connection is 65 established between the interior of the bomb

and the manometer. On lowering the bomb into position the mercury in cup 4 displaces any adhering air or water from the lower end of the bomb.

It is to be noted that the valve 23 is closed 70 only during the short interval of time necessary for securing the filled bomb in place in its socket, and during this time the bomb is under slight internal pressure thereby preventing leakage of air into the bomb.

The agitating device is then started and the temperature brought to the desired point. This is continued for a sufficient time to permit the apparatus to reach a uniform temperature, to establish equilibrium 75 between the phases, and uniformity of composition of the material of the phases, after which the desired manometer readings may be made.

It will be readily understood that if the bomb is completely filled with liquid at the beginning of the test the only vapor space that will be developed will be filled with only the vapors resulting from increase of 80 temperature and agitation. Due to the operation of the agitator in drawing the liquid from beneath the surface and projecting the same into the small vapor space in the form of a fine spray, the proportions of the constituents of the liquid in the various parts 85 of the bomb will be substantially identical, and the same is true of the vapor. Furthermore, since the higher boiling components and lower boiling components are all 90 projected into the vapor space equally, each has an equal opportunity to vaporize. Thus, each component of the mixture is brought to phase equilibrium without appreciable change of the proportions of the mixture such as would occur if a relatively 95 large vapor space were used. By this apparatus, the common errors in previous vapor pressure tests are substantially eliminated and the manometer readings obtained afford an accurate and direct measure of the 100 true vapor pressure of the mixture under test without the necessity of calculations.

Having thus described apparatus illustrating my invention, what I claim as my invention is:

1. In a device of the kind described, a container adapted to contain fluid, an induction driven device for homogenizing the components of fluids within the container, and a liquid sealed connection for transmitting the pressure within the container to a pressure measuring device.

2. In a device for generating vapor pressure to be measured, a fluid tight container, a tube within said container provided with an inlet and a restricted outlet, an induction driven device for producing phase equilibrium of the contents of the container by inducing a flow of fluid from said inlet through said outlet and means for trans-

mitting pressure developed within the container to a pressure indicator.

3. In a device of the kind described a vertically disposed elongated chamber adapted to contain a fluid and having a reduced upper portion constituting a vapor chamber, a vertically disposed tube within said chamber, said tube having an inlet and a reduced outlet adjacent and in axial alignment with and opening into said vapor chamber, an induction driven device for homogenizing the components of fluids within the container, and means for transmitting pressure developed within the chamber to a pressure indicating device.

4. In a device of the kind described, a vertically disposed elongated chamber for containing fluid, a longitudinally disposed tube within the chamber, a longitudinally disposed shaft provided with propeller blades within said tube, and an induction driven device for rotating said shaft to induce a flow of fluid through said tube to produce phase equilibrium and means for transmitting pressure developed within the chamber to a pressure indicator.

5. In a device of the kind described a vessel adapted to contain a temperature controlled fluid, a socket within the lower portion of said vessel, an upstanding flange about said socket forming a cup adapted to contain a fluid heavier than said first mentioned fluid, a closed bomb adapted to be substantially immersed in said temperature controlled fluid and having a lower portion adapted to be inserted in said socket, a valve in the lower portion of said bomb, and means in the socket for opening said valve when said lower portion is inserted in said socket.

6. In a device of the kind described, a vessel adapted to contain a temperature controlled liquid, a vapor generating chamber adapted to be inserted in said vessel, an induction motor, the rotor of said motor being located within said vapor generating chamber, and a second chamber containing the stator of said motor adjacent said first chamber when in assembled relation, said second chamber maintaining said stator out of contact with said liquid.
